UNITED STATES PATENT OFFICE.

CHARLES L. LAWTON, OF HANCOCK, MICHIGAN.

SKIP-DUMP.

1,151,955.

Specification of Letters Patent. Patented Aug. 31, 1915.

Application filed April 16, 1915. Serial No. 21,773.

To all whom it may concern:

Be it known that I, CHARLES L. LAWTON, a citizen of the United States, residing at Hancock, in the county of Houghton and 5 State of Michigan, have invented a new and useful Skip-Dump, of which the following is a specification.

In deep shaft mining, after the ore has been removed from the upper levels and the 10 shaft is extended downwardly, it becomes necessary to fill in some or all of the stopes. It is desirable that at least a part of the material be sand since it is less compressible than loose stone and fills the voids therein. 15 The sand and other substances have been delivered to the stopes by sluices, compressed air or skips, but the two first mentioned modes are objectionable for various reasons, and much difficulty has been experienced 20 with the skips because no means was available whereby they could be properly handled to meet all conditions under which it was desired to use them.

The present invention relates to a device 25 so arranged that the skip may, if desired, be filled with sand at the surface, then lowered and dumped at any preferred place without stopping, then filled with poor rock at the point where the shaft is being excavated, then elevated to the place previously 30 referred to and dumped, then elevated further and filled with rich ore and finally returned to the surface. Besides the cycle of operations referred to, the device is capable 35 of other modes of use, as will be apparent from the description.

In the drawings, Figure 1 is a part-side view, part-section of an inclined shaft showing the relationship of the dump to a chute or storage space which is to be filled. Fig. 40 2 is a diagrammatic side view showing the skip in dumping position. Fig. 3 is a section on the line 3—3 of Fig. 2. Fig. 4 is a view from the upper end of the dump, the 45 movable rail sections being in lowered position. Fig. 5 is a fragmentary view on the line 5—5 of Fig. 1, parts being broken away.

In the embodiment of my invention shown, 1 indicates an inclined shaft, 2 a 50 sand chute or storage bin from which the material is taken to a stope (not shown) in any preferred manner, and 3 designates another passage through which material may be delivered to the shaft by means of chutes

or other devices (not shown). The shaft 55 has supported therein in any desired manner the usual track runners 4 and track rails 5, and mounted to travel on the track is a skip 6 having front wheels 8 and rear wheels 9, the tread of the latter being of wider gage 60 than the former. This skip is hauled in the shaft by a bail 10 (not shown in Fig. 1), pivoted thereto at 11 near its center of gravity, and the usual cable 12, and is provided near the upper side of its rear end with the 65 projecting rollers or studs 13, the purpose of which is hereinafter pointed out.

Rising from the runners at points adjacent the entrance to the stope or sand chute 2 are the uprights 16, the upper ends of 70 which may engage the roof of the shaft. These uprights are joined and braced by timbers or guide rails comprising an upper central member 18 parallel to the rails 5, and the end members 19 inclined in respect 75 thereto, the latter of which terminate a distance above the rails greater than the diameter of the wheels of the skip, and preferably have their lower faces curved away from the tracks 5, as indicated at 20. The 80 timbers 18 may be supplemented by similar timbers 21, the outer ends of which project beyond the corresponding ends of the timbers 18 and may be connected thereto by fillers 22. These timbers are preferably 85 faced by the metal strips 23 (Fig. 3) and are curved downwardly toward the tracks at each end as indicated at 24, for a purpose that will be pointed out later. Also joining the uprights 16 are timbers comprising the 90 central members 25 (preferably parallel to the members 18) and the end members 26 that may be substantially parallel to the lower edges of the corresponding members 19 and which likewise terminate a distance 95 above the rails greater than the diameter of the wheels on the skip. The timbers 25—26 may be faced with metal strips 28 (Fig. 3), and the posts may be lined and joined between the timbers 18—19 and 100 25—26 by linings 29 (Figs. 1 and 3) that may be of metal or, at least, faced with metal. These linings preferably extend downwardly to the runners 4.

Arranged to align with the lower ends of 105 the timbers 26 are the rail sections 30 that are mounted on pivots 31 in the brackets 32, bolted or otherwise secured to the adjacent

uprights 16. These rail sections may have integrally formed therewith the counterpoises 33 by which they are normally held in the position shown in Fig. 1, that is, removed from the tracks 5; and their outer ends may be bent or flattened at 34 to afford a broad bearing when in the position indicated in Fig. 2. The rail sections are controlled by the following mechanism:—Pivoted on a bracket 35 carried by a platform 36 (the deck 38 of which may be slotted at 39, Fig. 1) is a lever 40, from which a link 41 extends to a rocker 42 pivotally mounted on the platform at 43. The rocker may be provided with the counterpoise 44, and a link 45 connects it to an arm 46 rigid with a cross-shaft 48 mounted in brackets 49 on the track structure. Also rigid with the cross-shaft at each side is a two-armed lever 50, to one arm of each of which is pivoted a link 51 that is similarly connected to the corresponding counterpoise 33 of the lower rail section 30. The other arms of the levers are pivotally connected to links 52 that are, in turn, pivotally secured to the counterpoises of the upper rail sections.

Operation: The rail sections 30 and controlling parts are normally held in the position shown in Fig. 1 by the counterpoises 33 and 44, and the skip may pass through the dump in either direction without being affected thereby in any manner, the curved faces 20 insuring a ready entrance thereto. When, however, it is desired to dump sand or other material that is being lowered from the surface into the entrance to the stope, an attendant standing on the platform 36 grasps the lever 40 and overcomes the effect of the counterpoises 33—44, thus lowering the rail sections 30 into the position shown in Fig. 2. The skip or bucket descending, its broad-tread or broad-gaged rear wheels 9 engage the sections 30, while the narrower front wheels 8 remain on the track 5. As a result the skip or bucket is tilted (Fig. 2) and the material is discharged from its open front end, after which a further lowering of the skip causes it to assume its former relation to the track. Were no means provided to prevent it, the skip might overturn and remain so as the bucket is lowered, but the roller 13 is positioned to contact with the metal strip 23 on the timber 21 and limit the clockwise movement of the skip (Fig. 2). The linings 29 guide the wheels 9 and prevent lateral movement in case they lift from the timbers 18 during the tilting action. Precisely the same operation takes place when the bucket is to be dumped in its rising movement, that is, after being filled with poor rock at a lower level. It may then be filled with rich rock and transported to the surface.

The device is obviously of special value when applied for mining purposes, but it is

also apparent that it may be installed elsewhere advantageously in certain cases, and that the details of the construction may be modified without departing from the spirit of the invention. I do not, therefore, wish to be limited otherwise than as indicated in the subjoined claims.

I claim:—

1. Material handling mechanism comprising a track formed of parallel spaced rails, a bucket mounted to travel back and forth thereon, said bucket including front and rear sets of supporting wheels, one set of wheels being of broader tread than the other, bucket dumping means along the track, said dumping means including a central track section spaced from and above the track, and switch sections, one pivoted at each end of the central track section, the free ends of said switch sections being movable toward and from the track and being arranged to intercept the wheels of wider tread when in one position whereby the bucket, upon entering the dump from either direction, is first caused to tilt about the axis of the wheels of the lesser tread and to thereafter return to its previous relation to the track as it passes off the dumping means onto the track in its continued movement in the same direction, the switch sections, when in another position, allowing the bucket to pass freely through the dumping means, means for normally holding the switch sections in one position, a lever, and means for connecting the lever to both of the sections whereby they may be simultaneously moved to the other position.

2. Material handling mechanism comprising a track formed of parallel spaced rails, a bucket mounted to travel back and forth thereon, said bucket including front and rear sets of supporting wheels, one set of wheels being of broader tread than the other, bucket dumping means along the track, said dumping means including a central track section spaced from and above the track, and switch sections, one pivoted at each end of the central track section, the free ends of said switch sections being movable toward and from the track and being arranged to intercept the wheels of wider tread when in one position whereby the bucket, upon entering the dump from either direction, is first caused to tilt about the axis of the wheels of the lesser tread and to thereafter return to its previous relation to the track as it passes off the dumping means onto the track in its continued movement in the same direction, the switch sections, when in another position, allowing the bucket to pass freely through the dumping means, means for normally holding the switch sections in the last named position, means for moving them to the first named position at will, and a guide rail substantially parallel to and lo-

cated above the central track section a distance slightly greater than the diameter of the wheels of wider tread, whereby said wheels are prevented from being thrown off 5 the central track section.

3. Material handling mechanism comprising a track formed of parallel spaced rails, a bucket mounted to travel back and forth thereon, said bucket including front and 10 rear sets of supporting wheels, one set of wheels being of broader tread than the other, bucket dumping means along the track, said dumping means including a central track section substantially parallel to the track, 15 inclined sections at the ends of the central track section and switch sections, one pivoted to each inclined end section, the free ends of said switch sections being movable toward and from the track and being arranged to 20 intercept the rear wheels of the bucket when in one position whereby the bucket, upon entering the dump from either direction, is first caused to tilt about the axis of the wheels of lesser tread and to thereafter re- 25 turn to its previous relation to the track as it passes off the dumping means onto the track in its continued movement in the same direction, the switch sections, when in another position, allowing the bucket to pass 30 freely through the dumping means, means for normally holding the switch sections in one position, means for moving them to the other position at will, and a guide rail having a central section and end sections, sub- 35 stantially parallel, respectively, to the central and end track sections of the bucket dumping means and located above the said track sections a distance slightly greater than the diameter of the wheels of wider 40 tread, whereby said wheels are prevented from being thrown from said track sections.

4. Material handling mechanism including an inclined track, a bucket mounted to travel back and forth thereon, said bucket 45 including front and rear supporting wheels, bucket-dumping means along the track, said dumping means including members movable in respect to the track and means for moving the members, and being arranged, when the 50 members are in one position, to cause the bucket to tilt about the axis of one of the wheels as it passes along the track in either direction, and, when in another position, to allow the bucket to pass freely along the 55 track, and means for limiting the tilting

movement of the bucket whereby it is prevented from accidentally overturning.

5. Material handling mechanism including an inclined track, a bucket mounted to travel back and forth thereon, said bucket 60 including front and rear supporting wheels, bucket-dumping means along the track, said dumping means including members movable in respect to the track and means for moving the members, and being arranged, when the 65 members are in one position, to cause the bucket to tilt about the axis of one of the wheels as it passes along the track in either direction, and, when in another position, to allow the bucket to pass freely along the 70 track, and means for limiting the tilting movement of the bucket whereby it is prevented from accidentally overturning, said limiting means including a track section on the dumping means and a projection on the 75 bucket arranged to contact with the track section as the bucket moves through the dumping means.

6. Material handling mechanism including an inclined track, a bucket mounted to 80 travel back and forth thereon, said bucket including front and rear sets of supporting wheels, the width of tread of the front wheels being different than that of the rear wheels, bucket-dumping means along the 85 track, said dumping means including a fixed track section above the track, and a movable track section at one end of the fixed track section, said movable track section, when in one position, allowing the bucket to pass by 90 the dumping means without being affected thereby, and when in another position, being arranged to guide one set of the bucket-supporting wheels from the track to the fixed track section and to permit the other 95 set of wheels to pass along the track, whereby the bucket is tilted about the last-named wheels to discharge its contents, means for limiting the tilting movement of the bucket, said means including a projection on the 100 bucket and a track section on the dumping means.

In testimony whereof I sign this specification in the presence of two subscribing witnesses.
